MULTIPLE-MIXTURE DIE-CASTING METHOD AND MACHINE

Application filed August 11, 1927. Serial No. 212,178.

My invention relates to die casting machines or apparatus and method or process of die casting.

An object of the invention is to provide a method and apparatus or machine for multiple layer, metal or mixture die casting, whereby a bearing or other article to be die cast by the machine may be quickly produced with a body and lining of different layers of the same or different metals, that is the same metal with the different layers subjected to different pressures for varying the density, or a relatively thick body of one metal or mixture and a relatively thin lining or covering of another metal or mixture, although two or more alloys or mixtures may be employed in the production of a composite bearing or other article, such as a body layer of 92 per cent. zinc, 7.5 per cent. copper, and 5 per cent. aluminum or miscellaneous materials or other metals, and a lining layer of from 50 per cent. to 85 per cent. tin and the balance lead, thereby producing a die casting in which the use of a great quantity of some expensive metal such as tin in the whole thickness of the bearing instead of merely in the lining is obviated, and at the same time produce an economical bearing or other article which is practical and efficient as to wearing qualities and which can be quickly produced.

Another object is to provide a novel method and apparatus for producing oil grooves or the like in the bearing, the construction being such that the grooves are automatically formed in the second layer or lining in the operation of die casting the bearing, the groove-forming device being automatically depressed flush with the surface of the small diameter of the core and automatically projected for producing the grooves in the second layer before the die casting is ejected.

A further object is to provide a die casting machine having two or more furnaces or melting pots, each having movable ladles or containers for the metals, alloys or mixtures used in the die casting, which move to dip and fill the same and are then brought into position simultaneously or otherwise to discharge the contents thereof into the molds successively under air or other pressure admitted into the

containers to eject the fluid metal from the containers to inject the fluid metal into the dies under pressure or otherwise, the space in the die mold being enlarged by means of a movable core, having portions of different size or diameter or otherwise for accommodating the layers successively, after which the die is opened and the casting ejected.

A still further object of the invention is to provide for the ejection of the air from within the die mold in the casting of the first layer so as to exclude the latter from exposure to air and possible oxidation to which it is readily susceptible, by sealing all joints or escape openings with the spruce or metal forced into the same and by enlarging the space to receive the second layer, as by means of movement of the core, establishing a substantial or partial vacuum, thereby insuring proper fusion or union between the first or outer layer and the second or inner layer, which would otherwise be seriously interfered with by exposure of the first layer to air and oxidation on the exposed surface to which the second layer is joined.

Another object of the invention is to provide a die casting machine which is automatic in its operation and which carries out the successive steps quickly and in sequence for each die casting operation.

Other objects and advantages of the invention will be understood by reference to the following specification and accompanying drawings, in which I have illustrated a selected embodiment of the invention and in which drawings:—

Fig. 1 is a side elevation of the business or mold end of the die casting machine showing the novel construction.

Fig. 2 is a top plan view.

Fig. 3 is a horizontal longitudinal sectional view of the mold with the core in position for die casting the first layer.

Fig. 4 is a view similar to Fig. 3, with the parts in position during the die casting of the second layer.

Fig. 5 is a sectional view, taken on line 5—5 of Figure 3, of the mold with the parts operatively assembled or together in the die casting of the first layer.

Fig. 6 is a sectional view taken on line 6—6 of Figure 3, showing the oil groove forming member in position when the first layer is being die cast.

Fig. 7 is a view similar to Figure 6, taken 5 on line 7—7 of Figure 4, showing the oil groove forming member in position when the second layer is die cast.

Fig. 8 is a sectional view of an air valve 10 employed with the machine to eject the metals into the mold.

Fig. 9 is a perspective view of an oil groove forming member.

Fig. 10 is an end elevation of a die cast 15 half-bearing produced by the machine, and

Fig. 11 is an inside elevation or bottom view of the bearing shown in Figure 10 and illustrating the oil grooves.

Referring to the drawings in detail, 11 indicates a table or frame supported on legs 12, this table being the usual table employed in connection with die casting machines of the horizontal type, although it is to be understood that the invention is not limited in 15 its application to this particular type of machine but may be applied with equal facility, so far as the combination of parts and principles involved are concerned, to machines of the vertical or other type. Mounted in an opening 11' centrally of the table are two or 20 more melting furnaces or pots 13 and 14, heated by electric heating elements or otherwise, as indicated at 15, and having at the top suitable bearings 16. The furnaces or 25 pots 13 and 14 may have suitably apertured lugs for bolting the same to the top of the table 11, as indicated at 17, and the furnaces taper toward the opposite ends, as shown more particularly in Figure 2 of the drawings. The bearings 16 take a pivot or shaft 30 30 on which are pivotally mounted against endwise movement, as by spacing sleeves or thimbles 16', ladles or containers 19 through 35 openings 20 in the shanks 21 thereof. The ladles or containers 19 are of hollow formation and are cut on a concavo-convex arc with a hollow containing space 22 having an internally threaded opening 23 communicating with its inner end and having at its outer 40 end an apertured plug or mouth portion 24 adapted to engage suitable inlet orifices or recesses in the die molds, as will be later described.

The opposite ends of the ladles 19 have the 45 shanks 21 extended downwardly beyond their curved portions and connected by a link 25 through equalizing springs 21' with a lever 26 fulcrumed intermediately and 50 adapted to be oscillated by a suitable means such as an eccentric roller, or otherwise, as is 55 common in the art, for moving the ladles on their pivots simultaneously from a normally lowered position to raise or swing the same upwardly and by engagement of the roller 60 with the lever to momentarily hold the ladles 65

with their mouth portions in positive operative engagement with the mold orifices. The link 25 has a cross arm 22' receiving bolts 23' on which the springs are mounted to rest on the shanks 21 which also receive the bolts to insure the proper seating of the ladles against the die mold and permit adjustment and equalizing of the tension. These ladles are adapted to dip in the molten metal in the furnaces or pots 13 and 14 and are curved on such an arc that when they are raised, they will fill with the metal through the mouth portions thereof. It is to be understood that the ladles may be actuated by the mechanism usually employed for raising the pot or ladle modified as described, or otherwise. Communicating with the ladles or containers 19 through the openings 23 by means of hose or pipes 27 and 28 is a control valve 29 which may be constructed as shown in Figure 8. As 70 illustrated, the valve is of the cylinder or piston type having a cylindrical casing with an inlet 30 at one end and an inlet 31 at the other for air under pressure and having an exhaust outlet 32 centrally at the bottom or at a diametrically opposite point on the cylinder 75 with respect to the inlets 30 and 31.

The cylinder also has an outlet port or opening 33 disposed inwardly of the inlet 30 and an outlet 34 disposed inwardly of the inlet 31 and in alignment with the exhaust outlet 32 as well as diametrically opposite the inlets 30 and 31 or otherwise, but staggered axially with respect thereto. A piston 35 is movable in the cylinder or casing 28 and has a reduced central portion and enlargements 36 at the ends, providing an intermediate annular opening 37. This piston is adapted to be actuated by a stem or rod 38 which passes through a suitable packing gland 39 in the open end of the casing 29 and is preferably detachably engaged with the piston as indicated at 40. This piston may be actuated by suitable means intermittently to admit air pressure into the ladles in the sequence required after the ladles are raised. The rod 38 is connected by a short link 41 to the upper end of a lever 42 fulcrumed intermediately at 43 and having the lower end pivoted to one end of a rod 44 extending along the side 48 of the machine and actuated by a cam or disk having an adjacent recess and raised portion successively disposed on its periphery so that the inlets and outlets are successively covered and uncovered to their respective ladles and 53 to hold the valve in a neutral position during the greater portion of the time when the ladles are lowered.

The die mold arranged on the table over the furnaces and ladles consists of a stationary section 45 and a movable section 46 properly formed to conform and produce the article to be die cast, such as a half-bearing, as shown in the drawings. The cavity or space within the mold for receiving the metal of the 58

die casting is designated at 47. In Figure 5, the sections of the mold are shown together and receiving a core 48, shown for constructional purposes as being formed of two sections held together at 49. This core has a large end 50 with a somewhat reduced portion 51 and a still smaller portion 52.

This core is fixed at its outer end to a plate 53 which is laterally adjustable and secured 10 at 54 to a slide 55 which slides laterally on a track 56 of a bracket 57 bolted to the table, which serves to guide the core horizontally. For actuating the core, the latter may be operatively connected at its outer end with an 15 arm 58 fixed to a shaft 59 bearing in the bracket 57 at the side of the table and adapted to be actuated by cams or other means suitably actuated by the mechanism of the machine in properly timed relation with the 20 other mechanism for moving the core inwardly between the sections of the mold and for successively moving or stepping it outwardly in the successive steps of a plurality in the die casting operation when two or more 25 metals, alloys or mixtures are forced or ejected into the mold cavity for producing the article to be die cast, as will be particularly described in connection with a half-round bearing, although it is to be understood that various other articles may be made in substantially 30 the same manner.

The movable section 46 of the die is adapted to be actuated by means of a slide mechanism 60 actuated by a suitable cam, drum and 35 toggle mechanism on the machine and having a stationary part 61 bolted on the table, or otherwise, and braced by the rod 62. Die blocks or shoes 63 are fitted against and secured to the movable and stationary sections 40 46 and 47 and the die block of the movable section has a sleeve 64 to take a plunger 65 with connected plates 66 at the inner end thereof within the chamber of the die block, and has push-out pins 67 to engage through 45 corresponding openings in the section 46 to eject the article produced in the machine from the mold. An oil hole forming pin 68 also may be provided in the section 46 to supplement oil groove forming means, as will be 50 later described.

The mouths or orifices leading into the cavity 48 of the mold and which are flared to conform to the mouth portions 24 at the outlet ends of the ladles or containers 19 are 55 designated at 69 and have neck portions 70 with one of which a sprue lock or valve 71 cooperates. This sprue lock passes through the sprue 72 at the neck part 70 and is adapted to be actuated by suitable rack and pinion or 60 other mechanism common in the art for reciprocating the lock or valve which incidentally serves to move the sprue 72 along for discharging the latter and simultaneously acting as a plug or valve to close the cavity 65 and prevent the passage of metal of the

second layer into the orifice of the ladle from which the metal for the first layer has been discharged. When the core 48 is shifted, a substantial or partial vacuum in the space of the die mold is established, and oxidation of the exposed surface of the first layer is thus prevented so as to secure more effective fusion or union between the layers of the article such as would be prevented by surface oxidation and the formation of a powder or loose coating on the exposed surface if it were subject to exposure to air and consequent oxidation. It is also understood that this partial vacuum is sealed by closing of the joints between the mold sections or special escape slots or openings provided for this purpose, owing to the air and sprue being forced out between the joints of the sections of the mold when the metal under pressure is forced into the cavity thereof during the first step of die casting operation. By this means, the joints between the sections are effectively sealed and the cavity rendered practically air-tight before the second layer or lining of the article is formed.

The cavity 47 is adapted to receive the first mixture or layer 73 when the core is in the position shown in Figures 3 and 5, said cavity having deeper portions at the ends to produce the end flanges 74 of a half-bearing. In this position, the ladles or containers 19 in the pots 13 and 14 have been dipped and raised to fill the same with the molten metal and to bring the mouth portions 24 thereof against the orifices 69, after which, air under pressure or otherwise is admitted into the ladle to inject the metal into the cavity 47. This is admitted into the pot containing the first layer mixture only, through the inlet 75 of the valve 29, in which position the piston 35 has been shifted to the right from the position shown in Figure 8 to uncover the outlets 33 and 34, allowing the air to enter one ladle through outlet 33 and exhaust compressed air in the other ladle through the outlet 34 and space 37 and port 32 to the atmosphere. The core is then moved from the position shown in Figure 3 to the position shown in Figures 4 and 7 to displace the portion 51 and the shoulder or lip 76 from the layer 73 so that the smaller portion 52 of the core is in alignment with the cavity 47 and the first layer 73. In this position, the lip or shoulder 76 remains within and seals the space formerly occupied by the large part 50 of the core 48 at the left-hand end between sections 45 and 46, and the lip or shoulder 77 seals the space 78, and the second ladle or container 19 within the pot 14, having also been swung against the orifice 69, air is admitted through the pipe 79 into the valve 29, and the piston 35, having been moved to the left to again uncover the outlets 33 and 34, air enters the inlet 31 and the pipe 27 through the outlet 34 for ejecting the babbitt or other mixture of 130

molten metal from the ladle, and allows air in the other ladle to escape to the atmosphere through the port 33 and exhaust 32.

It is to be understood that the pipes 27 and 28 are connected to the inlet openings 23 of the ladles and that the discharge of the metal is through the outlet orifices at the mouth portions 24 of the ladles. The cavity being entirely sealed, oxidation of the exposed surface of the layer 73 is absolutely prevented, and during the shifting of the piston 35 compressed air in the ladles exhausts through the port 32 to the atmosphere. Obviously, the movement of the piston 35 is in timed relation to the other mechanism so that the parts are operated in proper sequence. The babbitt or other mixture forming the inner layer of the article die cast by the machine, such as the bearing indicated, is shown at 80. 20 When this is formed, the die mold is opened while the core has its smaller portion of diameter opposite the cavity, by movement of the movable section 46 with respect to the stationary section 45. After this, the push-out pins are operated to displace the casting, the ladles having been previously lowered and the sprue lock or valve having been retracted or backed up to open the inlet portion 70 of the orifice 69.

Should it be desired to form oil grooves in the bearing, such means may be provided in the form of a groove forming member or maker 81, shown in Figures 3, 4, 6, 7 and 9. This member has four rings 82 at the proper angle and provided with bottom recesses 83, the ends of which are extended to produce under-cut portions 84 adapted to receive and retain therein an arcuate spring 85, these parts being fitted in a slot or seat 86 in the reduced portion 52 of the core 50 so that when the core is in the position shown in Figures 3 and 6, this groove-forming member is depressed into the small portion of the core flush with the operative surface thereof. 40 When the die mold is closed, and after the zinc or first layer has been formed, the core is shifted laterally to move the small diameter 52 opposite the same as shown in Figure 4. In this position, the spring 85 straightens and forces the member 81 out into the recess 78, so that when the inner layer 80 is produced it will have the grooves 87 therein produced automatically in the die casting operation. Incidentally, it will be noted that the rings 82 of the groove forming member close the opening where the pin 68 is positioned so as to form the oil hole 88.

This operation is continued for the die casting of each part or article, and it is, of course, to be understood that the shape of the article determines the shape of the concavity in the mold. It also is to be understood that the cores may be slid laterally from one or both sides and that the number of furnaces or pots for 60 the molten metals or mixtures may be in-

creased and that a movable ladle is provided for each pot. The elements 15, while described as electric heating elements of resistance wire, can be substituted by other heating means. In the formation of the oil grooves, when the core is partly drawn out to permit the projection of the oil maker or groove forming member 81 by the spring 85, the die mold is closed and the bearing or other article is ejected after the mold has been opened, due to the movement of the section 46 away from the section 45. This permits the core 48 to be pushed into its original position, as shown in Figure 3, and the closing of the mold section 46 against the section 45 depresses the groove forming member 81 into the recess of the small core portion 52, so that the portion 51 is in position to permit the formation of the layer 73. This operation may be quickly carried on to economically produce an article of composite metals or mixtures having two or more layers. The devices may also be applied to standard machines for die casting, such as the type illustrated in Figures 1 and 2 with the novel features applied thereto.

Die casting machines, especially those of the horizontal type to which the invention is shown applied, are usually controlled by a hand lever. Such a machine is operated by a belt pulley running at about 75 R. P. M. with a shaft driving pinion meshing with an integral gear resulting in a speed of 9 R. P. M. of drums controlling the operation or about $6\frac{2}{3}$ seconds per cycle of operation. The drums are right and left-hand due to outer cam arrangements and are bolted together with fitted bolts having a filler between the drums. The sides of the drums are provided with cam-ways in which disks run, one disk being fastened on each side of a lever which fulcrums on the end plate of the bed plate of the table and the other end transmits a vertical or downward motion to two levers, one on each side of the first lever, from which motion is transmitted to a toggle. One end of the toggle is fastened to the bed plate fulcrum stand and the other end to the main slide. When the drums revolve, the slide moves backward and forward toward and away from the stationary die holder or block. After the die mold has been fastened to the stationary and movable die holder and the drums have been revolved so that the toggle is in a straight line position, then the metal is forced into the die mold under pressure. While the drum is revolving, the die mold is closed, the metal containers rise into position, the cores are located, and the air pressure turned on automatically, after which the air is released, the containers dropped, the die mold opened, and the casting ejected from the die mold. The sequence of operation with the present machine is as follows:

First, the hand lever above referred to for

controlling the operation, is thrown over to the right, which lifts the pulley brake throwing out the automatic stop, and throwing in the countershaft clutch (not shown). The 5 drums revolve to straighten the toggle and close the die mold by shifting the movable section against the stationary section, after which the ladles or containers are lifted into place and air pressure admitted into the zinc 10 or first mixture ladle for forcing the same into the cavity of the die mold. The sprue lock then closes the inlet aperture of the die mold, after which the core is moved to dispose its small portion or diameter opposite 15 the cavity in the die mold in which the first layer or body of the die casting has been formed. Air pressure is then admitted into the babbitt or second mixture ladle to exit the molten metal or mixture and produce 20 the inner layer or lining of the die casting and the parts are lowered, after which the die is opened by further rotation of the drum and the raising of the toggle. The sprue lock then backs up and the push-out pins are 25 finally actuated to push out the casting. This operation is repeated by moving the core in, so that its largest diameter is opposite the cavity of the die mold, which is the first position in the die casting operation. 30 Then the movable section of the die mold moves up to close the die mold by the straightening of the toggle. This operation is quickly carried on and the ejection of one mixture or metal is almost instantaneously after the 35 other mixture or metal is injected. Obviously, the cavity may be enlarged one or more times to take two or more metals or mixtures, thereby producing a bearing or other article with two or more layers, according to the 40 requirements, though two are usually sufficient. The number of enlargements of the cavity depends upon the number of step portions which the core has. While I have shown a core which is movable laterally, it 45 is to be understood that it may be moved in any other direction than horizontally and that the enlargement of the cavity may be produced in any other suitable manner.

While I have shown and described my 50 invention in a preferred form, I am aware that various changes and modifications may be made therein without departing from the principles of the invention, the scope of which may be determined by reference to the 55 appended claims.

I claim as my invention:

1. A die casting machine having a plurality of melting furnaces, each having movable metal containers to inject fluid metal 60 into a die under pressure.

2. A die casting machine having a plurality of melting furnaces, each having movable metal containers, a mold having a cavity with means for enlarging the same, the 65 containers being adapted to be moved and

brought into position to inject different fluid metals from the furnaces into the cavity under pressure, and means for actuating said containers.

3. A die casting machine having a plurality of melting furnaces, each having movable metal containers, a mold having a cavity with means for successively enlarging the same, the containers being adapted to be simultaneously brought into position to inject different fluid metals from the furnaces into the cavity under pressure, said mold having separable parts, the joints between which are sealed by the metal upon the injection from the first container to expel air 70 from the mold cavity whereby to establish a partial vacuum within the cavity and prevent oxidation of the exposed surface of the metal upon the enlargement of the cavity and the proper fusion of the second metal therewith. 75

4. In a die casting machine, a plurality of melting furnaces, movable ladles in each furnace adapted to dip in the metal thereof for filling the ladles at their free ends, and means 80 for ejecting said metals independently. 85

5. In a die casting machine, a plurality of melting furnaces, movable ladles in each furnace adapted to dip in the metal thereof for filling the ladles at their free ends, means 90 for ejecting said metals independently, said means including a valve having inlets for the admission of pressure and outlets connected to the ladles, and means for actuating the valve. 95

6. A die casting machine having a plurality of melting furnaces, each having movable metal containers, a mold having a cavity, means for enlarging said cavity to take a plurality of layers of metal discharged 100 from the ladles, the containers being adapted to be simultaneously brought into position to inject different fluid metals from the furnaces into the cavity under pressure, and means for sealing the cavity. 105

7. A die casting machine having a plurality of melting furnaces, each having movable metal containers with outlet orifices, and means connected to the containers to inject fluid metal into a die mold under pressure. 110

8. A die casting machine having a plurality of melting furnaces, each having movable metal containers with outlet orifices, means to force molten metal from the containers under pressure at different times, a separable die mold having a cavity, a core for successively enlarging the cavity to receive successive layers of the molten metal, and means for sealing openings or joints in 120 the die mold upon the formation of the first layer of metal and for establishing a partial vacuum therein upon enlargement of the cavity to prevent oxidation of the first layer. 125

9. A die casting machine having a plural- 130

ity of melting furnaces, each having movable metal containers with outlet orifices, means to force molten metal from the containers under pressure, a separable die mold having a cavity, a core for enlarging the cavity to receive layers of the molten metal, and means for sealing openings or joints in the die mold after the formation of the first layer of metal, said mold having an inlet orifice and a sprue lock for closing said orifice.

10. A die casting machine having a plurality of melting furnaces, each having movable metal containers with outlet orifices, means to force molten metal from the containers under pressure at different times, a separable die mold having a cavity, a core for successively enlarging the cavity to receive successive layers of the molten metal, and means for sealing openings or joints in the die mold upon the formation of the first layer of metal, said die mold having inlet orifices to receive the mouth portions of the metal containers, a valve cooperating with one of said orifices to close the same after the injection of the first layer of fluid metal, and means for actuating said valve.

11. A die casting machine having a plurality of melting furnaces, each having movable metal containers with outlet orifices, means to force molten metal from the containers under pressure at different times, a separable die mold having a cavity, a core for enlarging the cavity to receive layers of the molten metal, and means for sealing the die mold upon the formation of a layer of metal, said die mold adapted to receive the metal from the outlet orifice of the metal containers, means cooperating with at least one of said orifices to close the same after the injection of said layer of fluid metal, means for ejecting the article produced in the cavity upon the separation of the die mold and means for closing said die mold after ejection of the article and prior to again receiving the molten metal.

12. A die casting machine having a plurality of melting furnaces, each having movable metal containers with outlet orifices, means to force molten metal from the containers under pressure at different times, a separable die mold having a cavity, a core for successively enlarging the cavity to receive successive layers of the molten metal, means for sealing openings or joints in the die mold upon the formation of the first layer of metal, said die mold having inlet orifices to receive the mouth portions of the metal containers, a valve cooperating with one of said orifices to close the same after the injection of the first layer of fluid metal, and an oil groove forming member carried by the core.

13. A die casting machine having a plurality of melting furnaces, movable metal

containers with outlet orifices near one end, means to force molten metal therefrom under pressure, a separable die mold having a cavity, a relatively movable core for successively enlarging the cavity to receive successive layers of the molten metal, means for sealing openings or joints in the die mold upon the formation of the first layer of metal, said die mold having inlet orifices to receive the outlet orifices of the metal containers, a valve co-operating with one of said orifices to close the same after the injection of the first layer of fluid metal, an oil groove forming member adjustably mounted in and carried by the core normally depressed so as not to project from the surface of the core, and means to project the same into the enlarged cavity when the core is moved, to form oil grooves when another layer of molten metal is injected into the cavity.

14. In a die casting machine, a mold having sections, at least one of which is adapted to be moved relative to the other and having a cavity formed therebetween, means co-acting with said sections to enlarge or restrict the cavity thereof for successively receiving molten metal to produce a plurality of layers joined together by fusion, and oil groove and hole forming members carried by the last-named means and one section respectively.

15. In a die casting machine, a mold having sections, at least one of which is adapted to be moved relative to the other and having a cavity formed therebetween, a movable core co-acting with said sections to enlarge or restrict the cavity thereof for successively receiving layers of molten metal to produce a plurality of layers joined together by fusion, and means for actuating the core.

16. In a die casting machine, a mold having sections, at least one of which is adapted to be moved relative to the other and having a cavity formed therebetween, means co-acting with said sections to enlarge or restrict the cavity thereof for successively receiving molten metal to produce a plurality of layers joined together by fusion, and means for actuating the last-named means, said means having lips or shoulders adapted to seal the cavity in the different positions of enlargement or reduction.

17. In a die casting machine, a mold having a cavity with inlet orifices communicating with the cavity, one section being movable toward and away from the other, and a core having step portions engaging corresponding openings in the sections and co-acting with the cavity to enlarge or reduce the same for receiving a plurality of molten metal mixtures for producing an article of a plurality of layers.

18. A die-casting machine having a plurality of melting furnaces, a pivoted ladle in each furnace, each with an outlet orifice,

means connected to the opposite ends of the ladles to force molten metal therefrom under pressure, a separable die mold having a cavity, a core for enlarging the cavity a plurality of times to receive layers of molten metal, means for sealing the joints or openings in the die mold after the formation of a layer of metal, said die mold having one or more inlet orifices to receive the outlet orifices of the 5 ladles, and means for closing said orifices at different times after injection of a layer of molten metal.

19. In a die-casting machine, a mold having sections at least one of which is adapted 15 to be moved relative to the other and having a cavity formed therebetween, a slidable core co-acting with said mold sections to enlarge or restrict the cavity thereof for successively receiving layers of molten metal to 20 produce a plurality of layers joined together by fusion, and means for actuating the core.

20. In a die-casting machine, a mold having sections, at least one of which is adapted to be moved relative to the other, and having 25 a cavity formed therebetween, automatic means cooperating with said sections to enlarge or restrict the cavity for successively receiving layers of molten metal, means for expelling the air from within the cavity, and 30 means for actuating the first-named means to move it outwardly and to move it in after the die is ejected.

21. The process of making a die cast article composed of a plurality of molten 35 charges which consist in introducing the molten charge in a portion of a molding cavity, sealing said charge from atmosphere causing another portion of the molding cavity to be presented to a charging position and 40 then introducing another molten charge in said other portion of said cavity to join said charges together.

22. The process of die casting which consists in successively enlarging the molding 45 cavity, injecting a plurality of molten metal mixtures into the cavity and utilizing one of said mixtures to aid in sealing the cavity from atmosphere before the injection of the next mixture thereinto.

50 23. The method of die casting with a plurality of metals which consists in successively enlarging a molding space, injecting a plurality of molten metal mixtures into said space successively as it is enlarged, expelling 55 the air from within the space at the first injection and sealing said space against the entrance of air to provide a partial vacuum therein and prevent oxidation of the first injection upon enlargement of the space for 60 receiving the next injection whereby the two metal injections may be joined together.

24. The process of die casting with a plurality of metals which consists in filling a molding space with one molten metal under 65 pressure, enlarging the space and then filling

the enlargement with another metal under pressure and at the same time as said space is enlarged interposing a groove forming member in said cavity to cause a groove to be formed in the metal forced into said enlargement.

25. The process of die casting with a plurality of metals which consists in filling a molding cavity with one molten metal under pressure, enlarging the cavity while the metal is still hot, expelling the air from the cavity to prevent oxidation and then filling the enlargement of the cavity with another molten metal under pressure to cause the two metals to be joined together.

26. In a die casting machine, means for defining a molding cavity, receptacle means for molten metals, means for filling a portion of said cavity with a charge of said molten metals, means for presenting another portion of said cavity to a charging position and means for introducing another of said molten metals in said other portion to join the molten metals in said cavity together.

27. In a die casting machine, means for defining a molding space, receptacle means for molten metal, means for injecting a plurality of charges of said molten metal into said space and means for utilizing one of said charges to aid in sealing the space from atmosphere before the injection of the next charge therein.

28. In a die casting machine, means for defining a molding cavity, receptacle means for molten metal, means for filling the cavity with a charge of said molten metal, means for enlarging the cavity and means for then filling the enlargement of the cavity with another charge of molten metal to cause said two charges of metal to be joined together.

29. In a die casting machine, means for defining a molding cavity, receptacle means for molten metal, means for filling the cavity with a charge of said molten metal, means for enlarging the cavity, means for then filling the enlargement of the cavity with another charge for molten metal to cause said two charges of metal to be joined together, and means arranged to be positioned in said cavity prior to the injection of the second charge of molten metal therein to cause a groove to be formed in the second charge of metal as it is added to the first charge.

30. In a die casting machine, means for defining a molding cavity, receptacle means for molten metal, means for filling the cavity with a charge of said molten metal, means comprising a movable core for enlarging the cavity and means for then filling the enlargement of the cavity with another charge of molten metal to cause said two charges of metal to be joined together.

31. In a die casting machine, means for defining a molding cavity, receptacle means for molten metal, means for filling the cavity

- with a charge of said molten metal, means comprising a movable core for enlarging the cavity and means for then filling the enlargement of the cavity with another charge of molten metal to cause said two charges of metal to be joined together, said core including a plurality of different sized portions adapted to be successively moved into the cavity as the two charges are introduced therein.
- 10 32. In a die casting machine, means for defining a molding cavity, receptacle means for molten metal, means for filling the cavity with a charge of said molten metal, means for enlarging the cavity and means for then filling the enlargement of the cavity with another charge of molten metal to cause said two charges of metal to be joined together, said enlarging means including a core having
- 15 a plurality of different molding surfaces adapted to be successively introduced into the molding cavity as the charges are injected in the cavity.
